(**) Term: **14 Years**

(57) **CLAIM**

(21) Appl. No.: **29/341,677**

The ornamental design for a rail hanger for attachment to a shelf bracket, as shown and described.

(22) Filed: **Aug. 11, 2009**

DESCRIPTION

(51) **LOC (9) Cl.** **08-05**

FIG. 1 is an isometric view of the hanger showing the design

(52) **U.S. Cl.** **D8/373**

FIG. 2 is a top plan view of the hanger showing the design

(58) **Field of Classification Search** D8/367,
D8/373; 248/301, 304, 339

FIG. 3 is a bottom plan view of the hanger showing the design

See application file for complete search history.

FIG. 4 is a first side elevational view of the hanger showing
